UNITED STATES PATENT OFFICE.

FRANK E. WAKEFIELD, OF ELGIN, ILLINOIS, ASSIGNOR TO ILLINOIS WATCH CASE COMPANY, OF ELGIN, ILLINOIS, A CORPORATION OF ILLINOIS.

RECEPTACLE FOR ASHES AND THE LIKE.

Application filed May 10, 1926. Serial No. 108,068.

This invention which relates to a receptacle convenient for the deposit of ashes or other light materials is directed more particularly to a construction which may be accommodated within an outer case or housing. Articles of this general character are especially suitable for mounting upon fixed supports, such as the walls of a room or automobile body. The device herein shown and described is designed with this special purpose in view, although it might obviously be employed elsewhere to advantage.

It is a primary object of this invention to devise a receptacle of the kind mentioned which may be produced at small expense; which will be neat in appearance; which will retain its several components in securely assembled relation; which may be fitted easily within an intended case where it is held against movement; and which may be removed at will whenever desired for emptying of contents or any other purpose. Such a receptacle is illustrated in a preferred form in the accompanying drawing in the manner following:

Figure 1 is a perspective view of the receptacle per se;

Fig. 2 which is a vertical section through a case or housing shows the receptacle fitted therein in the intended manner; and

Figs. 3, 4, and 5 which are perspective views show, respectively, the three receptacle components—its upper edge, its body, and its separable side.

The receptacle A comprises in its structure a body (Fig. 4) having a bottom 6 from which upstand two end walls 7 connected by a side wall 8 which also is connected to the bottom. Such a structure may conveniently be produced from sheet metal by die operations which are well known and commonly employed. Projecting from the aligned free edges of the bottom and the two end walls are tongues 9, as shown.

Associated with such a body is a separable side 10 (see Fig. 5) having flanges 11 turned laterally from its bottom and vertical edges. These flanges are adapted to lap past the corresponding edges of the body bottom 6 and end walls 7 whereby to provide an enclosing structure open only upon the top. Slots 12 may be provided in the separable side adjacent its flanges to receive the tongues 9 which, upon being clinched, serve to secure this side permanently upon the body. If de-

sired, indentations 13 may be arranged adjacent each slot so as to accommodate the tongues therein in flush relation.

With a receptacle so formed, I may assemble a top edge component (Fig. 3) which is in the form of a rectangular ring 14 having an outstanding flange 15 adapted to overlie the upper edge of the body and side piece heretofore described. The ring which is fittable within the receptacle so formed may be provided on two of its opposite sides with aligned slots 16, and adjacent the slots in one ring side I have shown indentations 17. The number of such slots 16 is a matter of choice—two are shown on each of two opposite ring sides, but this may be either more or less, as desired.

A permanent assembly of the top edge component is accomplished by the use of bars 18, (see Fig. 6) one for each pair of slots 16. As shown, each bar may be curved downwardly and is formed to provide at one end a tongue 19 and at its other a depending spring 20 which is outwardly bowed. Adjacent the upper edges of the body side wall 8 and the separable side 10 are other slots 21 in register with those provided in the ring of the top edge component. Through these several registering slots, the bars may be extended to tie the top edge to the receptacle body and its separable side, the tongue ends 19 being thereafter clinched to make this relationship of the parts permanent. If desired, indentations 22 may be provided in the body adjacent the slots 21 which lie next to indentations 17 in the top edge piece, the displaced metal in the one part being thereby permitted to occupy the adjoining space so that the bar tongues 19 need not protrude beyond the outer face of the receptacle walls. It will be noted that, by the means described, the bars act as ties for holding the separable side to the body, and also secure themselves in place horizontally across the upper open side of the receptacle. The only protruding elements are the springs 20 which, as stated, are outwardly bowed for a purpose which will shortly appear.

A receptacle of this general kind may be fitted conveniently with a case or housing B (see Fig. 2). As shown, such a case may include side and end walls 23, and a bottom 24. Additionally, if desired, it may be enclosed within an ornamental outer shell 25 one wall of which may be upwardly extend-

ed as at 26 to assist in conveniently mounting the housing upon a wall. Around the upper edge of the case may be arranged a layer of felt 27 whereon is rested the outstanding flange 15 of the top edge component of the receptacle. Details of this character are of minor importance, and have been adverted to only to indicate one advantageous method of combining my present receptacle 10 with a case having certain meritorious features.

In use the receptacle is placed within the case which, of course, is properly dimensioned to receive it. The spring (or springs) 15 20 is forced to a position of compression when the receptacle is so disposed, and because of the pressure which it exerts against the proximate case wall the receptacle is pushed over into tight engagement with the 20 opposite wall. The receptacle is accordingly held securely against movement, and may not rattle around even though, as in the case of an automobile, the support for its mounting is unstable. And, as a further consequence 25 of the construction just described, the receptacle may, if desired, be withdrawn with ease by lifting up upon its outstanding edge flange which also is disposed exteriorly of the case. Across the bar or bars 18 any 30 small object, such as a cigarette, may be rested in a manner which will permit the ashes thereof to drop into the receptacle, and because of the downward curve in the bar such an object will be retained in a fixed position.

I claim:

1. A sheet metal receptacle in which is comprised a body having a bottom, two ends, and a side, a second side joined to the body 40 to form therewith an enclosure open only at the top, a top edge piece having a ring which fits around the upper portion of the receptacle walls, and an outstanding flange extending laterally therefrom, there being registering openings through opposite sides of the ring and receptacle walls adjacent thereto, and a bar extending across the receptacle 45 through the several openings to connect the edge piece to the receptacle, the bar having one end clinched against a receptacle wall and the other end laterally turned to provide a bowed spring, substantially as described.

2. A sheet metal receptacle of two parts 55 comprising a body and a separable side joined thereto forming an enclosure open only at the top, a top edge piece for the receptacle, and a tie bar extending crosswise between two of the receptacle walls, the tie bar 60 being also connected to the top edge piece

whereby to effect its securement to the receptacle, substantially as described.

3. A sheet metal receptacle of two parts consisting of a body and a separable side joined thereto forming an enclosure open only at the top, a top edge piece for the receptacle provided with an outwardly extending flange, a case in which the receptacle is fittable, and spring means interposed between adjoining walls of the receptacle and case 70 having a portion of itself interlocked with both the receptacle and top edge piece whereby to connect the one to the other, substantially as described.

4. A sheet metal receptacle of two parts 75 comprising a body and a separable side forming an enclosure open only at the top, tongues extending from the one part through the other and clenched thereupon to connect said side to the body, the walls adjacent the 80 clinched tongues being indented to receive the tongues in flush relation, a top edge piece surrounding the upper margin of the receptacle, and tying means extending across the receptacle and joined to the top edge piece to 85 secure the one to the other, said tying means being disposed slightly below the top edge piece and providing a sunken support on which an object may be rested, substantially as described.

5. In combination with a case, a receptacle fittable thereinto, a top edge piece for the receptacle having an outstanding flange adapted to rest upon the upper edge of the case, and means tying the top edge piece to 95 the receptacle and extending upon one side thereof in the form of a spring adapted to exert pressure against the proximate wall of the case whereby the receptacle is frictionally held against movement within the case, substantially as described.

6. A sheet metal receptacle open only at the top, an edge piece surrounding the upper receptacle edge and having a portion of itself depending adjacent a wall of the receptacle, and tying means independent of the edge piece extending through said depending edge portion and adjacent wall to connect the one to the other, and continuing across the receptacle to provide a support, substantially as described.

7. A receptacle having one separable side, a case in which the receptacle is removably fitted, and means connecting the separable side to the body extending exteriorly thereof in the form of a spring adapted to exert pressure against the proximate case wall when the receptacle is fitted in place, substantially as described.

FRANK E. WAKEFIELD.
